TRIGGER SAFETY FOR FIREARMS

Maruja Acosta de von Breymann,
San Jose, Costa RicaApplication December 30, 1948, Serial No. 63,217
In Costa Rica January 2, 1948

2 Claims. (Cl. 42—70)

1

This invention relates to firearms and more particularly to the kind which are provided with a trigger and a guard, for instance a rifle or pistol.

It is an object of this invention to provide a firearm of the mentioned kind with a safety device which prevents the trigger from being operated.

It is another object of this invention to provide a safety device which is clearly visible so that its being in position can be judged by an observer from a distance.

Other objects of the invention will appear from the following detailed description in connection with the accompanying drawings in which several embodiments of the invention are diagrammatically shown by way of example.

In the drawings:

Fig. 1 is a perspective view of a safety device according to the invention.

Fig. 2 is a side elevational view of the device shown in Fig. 1 when in position in a rifle.

Fig. 3 is a cross section along the line 3—3 of Fig. 2.

Fig. 4 is a view similar to Fig. 2 with the parts in different positions.

Fig. 5 is a second embodiment of the invention applied to a pistol.

Fig. 6 is a perspective view of the safety device shown in Fig. 5.

Figs. 7 and 8 are views of a third embodiment of the invention shown respectively in inoperative and operative position.

Fig. 9 is a section along the line 9—9 of Fig. 8.

Figs. 10 and 11 are views of another embodiment of the invention with the safety device respectively in inoperative and operative position,

Figs. 12 and 13 are similar views of still another embodiment of the invention.

Figs. 14 and 15 are views of another embodiment of the invention respectively in inoperative and operative position, and

Fig. 16 is a cross section along the line 16—16 of Fig. 14.

Referring now to the drawings and first to Figs. 1—4, 10 is a block which is shaped to fit into the guard 12 arranged on a rifle stock 14.

The block 10 is provided with a recess 16 which accommodates the trigger 18 of the rifle when the block 10 is inserted into the guard 12 from one side thereof. The block may consist of plastic material, light metal, wood or any other material. Preferably the block 10 is provided on the side where the recess 16 is provided with a cover 20 which has two flange parts 22 and 24. A screw

2

26 holds the cover 20 in position on the block 10. Between the cover 20 and the front side of the block 10 is left a space in which a circular disc 28 is slidably arranged. The circular disc or plate 28 is provided with a handle 30 which is slidably arranged in a horizontal slot 32 provided in the front part of the cover 20.

The operation of the safety device is as follows:

The block 10 with the plate 28 in its left-hand position according to Figs. 1 and 2 is inserted into the guard 12 of the rifle whereby the trigger 18 is accommodated in the recess 16. Then the

plate 28 is moved by pushing the handle 30 to the right so that it reaches the position shown in

Fig. 4 in which the trigger 18 is substantially covered from all sides. If desired the plate 28

may be secured in this position by a lock (not shown).

The plate 28 need not be circular in shape, nor

is the sliding arrangement indispensable. The plate 28 for instance could be provided with a recess having about a quarter of its area and

could be turnably arranged about its centre so as to cover the recess 16 in one position and to uncover the same in another position.

In another embodiment the plate is hinged to the block 10 so that in one position it covers the recess 16 and the trigger 18. In this case, the

cover 20 may be dispensed with.

The safety device may also be adapted to double barreled shotguns comprising two triggers by increasing the width of the block 20 and the recess 16.

Referring now to Figs. 5 and 6, 40 is a pistol

provided with a trigger 42 and a guard 44. In order to protect the guard 44 and the trigger 42

a cover 46 is provided which preferably consists of sheet metal or other resilient material. The cover 46 comprises two portions 48 and 50 covering the guard 44 on both sides, and a connecting portion 52. The walls 48 and 50 are provided with

dents 54 which cooperate with similar dents in the guard 44 so as to hold said cover in position on the guard. If desired, this device may be pro-

vided with means for blocking the trigger, for instance with leaf springs which catch the trigger from behind.

Referring now to Figs. 7—9, 14 is a stock of a rifle from which the guard 12 and the trigger 18

protrude. The stock 14 is provided with a recess 60 above the guard 12. A two-walled element 62

whose shape in its lower part corresponds to that of the guard 12 is movable so that in inoperative position it is inside of the recess 60 as shown in Fig. 7 whereas in operative position (Fig. 8) it

covers the trigger 18 on both sides thereof. The element 62 is provided with one or two flanges 64, which protrude at right angles to the walls of the element. These flanges 64 have a two-fold function. They serve as a handle for shifting the element in and out of operative position and secondly, they form stops by abutting against the rifle stock 14 in the uppermost position and against the guard 12 in the lowermost position of the element. 66 is a cross member such as a rivet or pin joining the two walls of the element 62 and locking the trigger 18 by abutting cooperation with same when the element is in its operative position. A bridge 68 joins the walls of the element 62 at their upper edges and is provided with a slot 70 for the trigger and its associate mechanism.

The operation of the safety device shown in Figs. 7-9 is as follows:

In the position shown in Fig. 7 the element 62 is retracted within the recess 60 of the rifle stock 14. If it is intended to protect the trigger against accidental operation, the element 62 is brought into the position shown in Fig. 8 by pulling the flanges 64 downwardly until they abut against the guard 12. In this position the cross member 66 locks the trigger against accidental discharge of the weapon. If it is desired to use the rifle again, the flanges 64 are pushed upwardly until they abut against the rifle stock 14.

Referring now to Figs. 10 and 11, 14 is again the rifle stock, 12 the guard and 18 the trigger. A pocket-shaped cover 80 is pivoted at 82 to the guard. The pivot 82 is arranged at the corner of said cover 80 and at one end of the guard 12 preferably behind the trigger 18 so that the cover 80 may be swung into and out of the guard cover position. 84 are projections arranged at the corner of the pocket opposite to the pivot 82. They serve for an easy handling of the cover 80. 88 is a pin or the like arranged in the cover 80 at an inclined position so that it comes into cooperative engagement with the lower end of the trigger 18 in the guard covering position of the cover 80. The pin 88 is provided with a head 90 and secured to the rim 92 of the cover. 94 is an opening in the guard 12 through which the pin 88 extends when the cover is brought into operative position.

The operation of this device is as follows:

If the rifle is to be used the cover 80 is swung to the back as shown in Fig. 10, the rifle butt being provided with a suitable recess (not shown) for accommodating the cover 80. If it is intended to secure the rifle against accidental discharge the cover 80 is brought into the position shown in Fig. 11 in which it covers the guard 12. In this position the pin 88 locks the trigger 18 against operation.

Referring now to Figs. 12 and 13, 14 is again the rifle stock, 12 the guard and 18 the trigger. The guard 12 is slotted over almost its entire length as shown at 102. Through this slot a block 104 may be inserted from below. The block 104 has a shape substantially corresponding to that of the guard, and is provided with a slot 106 for accommodating the trigger. Also the block 104 is recessed at 108 and 110 near its upper corners for a purpose presently to be explained. 112 is a strip made of resilient material such as metal which is secured by screws 114 and 116 to the block. The free ends of the strip are shaped as end pieces 118 and 120 provided with catches 122 and 124 cooperating with recesses 126 and 128 provided in the guard 12. 130 and 132 are knobs

for pressing the catches 122, 124 out of the recesses 126, 128.

The operation of this device is as follows:

When it is intended to insert the block 104 it is first brought into the position shown in Fig. 12 in which the block 104 is directly underneath the guard 12 with its upper margin in the slot 102. The block 104 is then pushed upwards until the metal strip 112 abuts with the slotted part 102 of the guard 12. In this position the free ends 112, 120 enter with their catches 122, 124 the recesses 126, 128 of the guard 12 so that the block 104 is securely secured in operative position. The trigger 18 enters the recess 106 of the block and as this recess has the minimum width corresponding to the trigger 18, it locks the trigger against a discharge of the weapon. If it is desired to remove the lock 104 from its operative position shown in Fig. 13 the knobs 130 and 132 are slightly pressed so that the catches 122 and 124 leave the recesses 126 and 128. The block 104 can then be withdrawn in a downward direction.

Referring now to Figs. 14-16, 14 is again a rifle stock, 12 the guard and 18 the trigger. Above 25 the guard 12 the rifle stock is provided with a recess accommodating a two-walled element 140 which has substantially the same configuration as the opening of the guard 12. The two walls of the element 140 are joined by a cross member 142 which in operative position of the guard lies behind the trigger 18 so as to lock the same by its cooperative abutment with the trigger. The two walls of the element 140 are provided with extensions 144 which are pivoted at 146 to the rifle stock 14. A coil spring 148 is provided around the fulcrum 146 and has one arm 150 fixed to the stock 14 at 152 whereas the other arm 154 presses against the element 140 and urges the same into operative position. 158 is a hole near the upper edge of one of said walls constituting the element 140 which in inoperative position of the element comes into engagement with a hook 160 which is secured to a leaf spring 162 or the like fixed with one end to the rifle stock 14. 164 is the other end of the leaf spring 162 protruding through a hole in the rifle stock 14 so that it can be pressed downwardly by hand thus releasing the hook 160 from the hold 158 so that the spring 148 brings the element 140 into operative position. A cross piece 166 arranged at the margin of the element 140 and knurled at its sides rests in inoperative position of the element in a recess 168 of the rifle stock.

The operation of this device is as follows:

In inoperative position shown in Fig. 14 the member 140 is in the recess inside the stock 14. In this position the hook 160 enters the hole 158 so that the element 140 is held against the force of the spring 148 which is in the state of compression. If it is desired to bring the element 140 into operative position shown in Fig. 15 the knurled end 164 of the leaf spring 162 is pressed into the rifle stock so that the hook 160 leaves the opening 158. Then the spring 148 turns the element 140 around its fulcrum 146 until the member 166 abuts against the guard 12. In this position the cross member 142 lies behind the trigger 18 so as to lock the same. If it is desired to return the element 140 into non-operative position shown in Fig. 14 it is turned in an anti-clockwise direction by means of the member 166 until the latter abuts against the recess 168 of the stock 14. Towards the end of this movement the hook 160 arranged on the leaf spring comes 75 to engagement with the hole 158 whereby the

hook 160 snaps into the hole 158 so that the element 140 is locked in inoperative position.

I have described preferred embodiments of my invention, but it is understood that this disclosure is for the purpose of illustration and that various omissions or changes in shape, proportion and arrangement of parts, as well as the substitution of equivalent elements for those, herein shown and described, may be made without departing from the spirit and scope of the invention as set forth in the appended claims. 10

What I claim is:

1. A firearm comprising: a trigger, a guard for said trigger, a block fitting in said guard, said block being provided with a recess for accommo- 15 dating said trigger, and a plate on said block movable between two end positions, said plate in one end position covering said recess.

2. A firearm comprising: a trigger, a guard for said trigger, a block fitting in said guard, said block being provided with a recess for accommo- 20

dating said trigger, and a sliding plate on said block movable between two end positions, said plate in one end position covering said recess.
